LOOM DOBBY

Joseph D. Cash, Jr., Cramerton, N. C.

Application September 26, 1945, Serial No. 618,630

5 Claims. (Cl. 139—74)

1

This invention relates to loom dobbies and has more particular reference to the provision of wear-resisting bearings for the hook levers and hooks of such dobbies.

Large numbers of hook levers are used in each loom dobbie, and they are extremely limited in thickness and are usually constructed of strips of relatively cheap and soft sheet metal having comparatively small resistance to wear. Accordingly, as the levers are subjected to often repeated, heavy strains, they rapidly wear at their pivots and at the pivots for the hooks. This results in loose pivots that cause faulty operation of the loom and require frequent replacement of the hook levers.

The primary object of the present invention, therefore, is to provide the dobbie levers with wear-resisting bearings of practical construction so that frequent replacement of the levers will be unnecessary even though said levers are mainly constructed of strips of relatively cheap and soft sheet metal.

The exact nature of the present invention, as well as other objects and features thereof, will become apparent from the following description when considered in connection with the accompanying drawings, in which:

Figure 1 is a side elevation of certain parts of a loom harness mechanism embodying the present invention.

Figure 2 is an edge elevational view looking toward the right of Figure 1.

Figure 3 is an enlarged fragmentary vertical section taken on the line 3—3 of Figure 1.

Figure 4 is a view similar to Figure 3 taken on the line 4—4 of Figure 1.

Figure 5 is a fragmentary developed perspective view showing the jack or harness lever, the hook lever, and the parts of the bearing for the hook lever in process of assembly.

Figure 6 is an enlarged fragmentary section taken on line 6—6 of Figure 1.

Figure 7 is a section taken on line 7—7 of Figure 6.

Figure 8 is a fragmentary elevation illustrating a modification of the pivot boss or stud for the jack or harness lever.

Figure 9 is a view similar to Figure 8 of a further modification.

Figure 10 is a section taken on line 10—10 of Figure 1, and

Figure 11 is a side view of one of the bearing rings for the pivot bosses of the hooks.

Referring in detail to the drawings, 5 indicates a jack or harness lever having an integral boss

2

or stud 6 on which the hook lever 7 is centrally pivoted, and 8 and 9 indicate the upper and lower hooks which are pivoted to the ends of the hook lever 7. As usual, the lever 7 is mainly constructed of two similar strips of sheet metal 10 and 11 suitably secured together as by rivets 12. To minimize cost, the sheet metal of which the parts 10 and 11 are formed is relatively soft material possessing comparatively little resistance to wear. These parts are formed in the shape shown in Figure 3 with the offset end portion 13 of parts 10 and 11 at opposite ends of the same and with lateral lugs or projections 14 on the straight ends of said parts or strips 10 and 11. The strips are then placed face to face with their intermediate portions in engagement, whereupon the parts are secured together by the rivets 12, the lug 14 of each strip contacting the adjacent end of the other strip so as to keep the ends of the strips 10 and 11 in properly spaced relation.

As shown, the pivot boss or stud 6 of lever 5 is of non-circular form in cross section and has at least one flat side 15. Fitted on the stud 6, by a snug or press fit, is an inner bearing sleeve 16 of cylindrical external form and provided with a central bore 17 substantially conforming in size and shape to the stud 6. The stud 6 and sleeve 16 are of similar length. The strips 10 and 11 have registered central pivot openings 18 of larger size than the stud 6 and sleeve 16, and tightly fitted in these openings with a press fit is an outer bearing thimble 19 having a cylindrical wall received in the openings 18, an outer end wall 20, and an external annular flange 21 on the inner end thereof. The sleeve 16 has a snug, rotating fit in the thimble 19, and the flange 21 engages the face of strip 10 adjacent the lever 5, being preferably countersunk in said face as shown so as to permit the strip 10 of the lever 7 to lie in contact with the adjacent face of lever 5. The flange 21 prevents displacement of the thimble 19 from the openings 18, and the wall 20 of the thimble 19 acts as a lubricant retainer when the lubricant is introduced between the parts 16 and 19 in process of assembly. The end wall 20 is preferably of slightly convex form so as to leave a slight space between the same and the outer ends of the parts 6 and 16 to act as a lubricant reservoir. Due to the form of the stud 6 and the bore 17, the bearing sleeve 16 is positively retained against turning, and the outer surface of the cylindrical wall of thimble 19 may be roughened so as to bite into the material of the strips 10 and 11 and thereby insure against turning of the thimble 19 relative to the lever 7.

A tight press fit of thimble 19 in openings 18 may, however, be found sufficient. In this way, a very practical and efficient wear-resisting bearing may be provided for the lever 7 even though the same is made of comparatively thin sheet metal strips of relatively soft quality, only the parts 16 and 19 being made of relatively hard, wear-resisting bearing material.

As usual, the hooks 8 and 9 are preferably provided with integral pivot bosses 22 at each side thereof which are ordinarily received in openings 23 in the ends of the lever strips 10 and 11, the pivoted end of each hook being freely movable between the ends of the strips 10 and 11 which are sufficiently separated for this purpose by the lugs 14. However, in accordance with the present invention, the openings 23 are made somewhat larger than the bosses 22, and a bearing ring 24 is tightly fitted in each opening 23 with a press fit. Each bearing ring 24 has a central opening 25 which is of a size so that a boss 22 has a snug pivotal fit therein. Obviously, the bosses 22 and bearing ring 24 may be formed of relatively hard, wear-resisting metal so as to insure long continued operation without wearing of the parts at the pivots for the hooks 8 and 9. If found necessary or desirable, the bearing rings 25 may be provided with transverse peripheral V-shaped ribs 26 which are comparatively fine and sharp and are, therefore, adapted to bite into the material of the strips 10 and 11 surrounding the openings 23 when said bearing rings 24 are pressed into place. This insures more positive retention of the bearing rings in place and prevention of the same from rotating relative to the strips 10 and 11 or with the bosses 22. Practical bearings are thus provided for the hooks 8 and 9 even though they are of limited width corresponding to that of the thickness of strips 10 and 11. Even though the hooks 8 and 9 and lever 7 are subjected to repeated strains, the bearings provided as described above effectively resist wear and eliminate the necessity for frequent replacement of the lever 7.

In the embodiment of Figures 1 to 7, inclusive, the stud 6 is of general cylindrical form with one flat side 15, but it will be apparent that rotation of bearing sleeve 16 may be prevented in other equivalent ways, such as by providing the stud 6a of rectangular form, as in Figure 8; or of hexagonal form, as shown at 6b in Figure 9. In all cases, the stud is of non-circular form in cross section and is adapted to be used with a bearing sleeve having a bore of similar form.

From the foregoing description, it is believed that the construction, operation and advantages of the present invention will be readily understood and appreciated by those skilled in the arts. Minor changes may be made in details of construction illustrated and described, such as fall within the scope of the invention as claimed.

What I claim is:

1. In a loom dobby, in combination, a jack lever having a pivot stud of non-circular cross section for a hook lever, an inner bearing sleeve 5 having a bore corresponding in shape to that of the pivot stud and fitted onto the latter, a hook lever embodying two sheet metal strips secured together and provided with central registered openings, and an outer bearing thimble having a snug rotating fit on said bearing sleeve and press fitted into said registered openings of the strips of the hook lever, said bearing thimble having a wall closing the outer end thereof and provided with an external flange at its inner end engaging the face of the strip adjacent the jack lever in surrounding relation to its opening.
2. The construction set forth in claim 1, wherein in said flange of the bearing thimble is countersunk in the adjacent face of the adjacent strip.
3. The construction defined in claim 1, wherein in the end wall of the bearing thimble is of convex form and spaced from the adjacent ends of the pivot stud and inner bearing sleeve to provide a lubricant reservoir.
4. In a loom dobby, a jack lever having a pivot stud for a hook lever, a bearing sleeve having a press fit on said stud, a hook lever including two strips of sheet metal secured together and provided with registered, central openings, and an outer bearing thimble having a press fit in said registered openings and a snug rotating fit on said inner bearing sleeve, said bearing thimble having a wall closing the outer end thereof and being provided, at its inner end, with an external flange engaging the face of one of said strips adjacent the jack lever to prevent displacement of the thimble from said registered openings.
5. The construction defined in claim 4, in combination with means to positively prevent relative rotation of the inner bearing sleeve relative to the pivot stud of the jack lever.

JOSEPH D. CASH, JR.
